(57) **CLAIM**

The ornamental design for an combined inflator mounting bracket and inflator, as shown and described.

DESCRIPTION

FIG. 1 is a perspective view of the combined inflator mounting bracket and inflator, according to one embodiment of this invention;

FIG. 2 is a front view of the combined inflator mounting bracket and inflator shown in FIG. 1;

FIG. 3 is a rear view of the combined inflator mounting bracket and inflator shown in FIG. 1;

FIG. 4 is a side view of the combined inflator mounting bracket and inflator shown in FIG. 1;

FIG. 5 is a side view, opposite the side view shown in FIG. 4, of the combined inflator mounting bracket and inflator shown in FIG. 1;

FIG. 6 is a top view of the combined inflator mounting bracket and inflator shown in FIG. 1;

FIG. 7 is a bottom view of the combined inflator mounting bracket and inflator shown in FIG. 1;

FIG. 8 is a top view of the combined inflator mounting bracket and inflator shown in FIG. 1 having an inflator mounted therein;

FIG. 9 is a bottom view of the combined inflator mounting bracket and inflator shown in FIG. 8;

FIG. 10 is a side view of the combined inflator mounting bracket and inflator shown in FIG. 8;

FIG. 11 is a side view, opposite the side view shown in FIG. 10, of the combined inflator mounting bracket and inflator shown in FIG. 8;

FIG. 12 is a top view of the combined inflator mounting bracket and inflator shown in FIG. 8; and,

FIG. 13 is a bottom view of the combined inflator mounting bracket and inflator, as shown in FIG. 8.

The broken lines are included for the purpose of illustrating portions of the combined inflator mounting bracket and inflator that form no part of the claimed design.
